UNITED STATES PATENT OFFICE.

FRED C. HOFFER, OF LOS ANGELES, AND J FRANK SMEDLEY, OF PASADENA, CALIFORNIA, ASSIGNORS TO MOTORCYCLE SWEeper COMPANY, OF LOS ANGELES, CALIFORNIA, A CORPORATION OF CALIFORNIA.

STREET-SWEeper.

1,369,106.

Specification of Letters Patent. Patented Feb. 22, 1921.

Application filed January 27, 1917, Serial No. 144,977. Renewed January 3, 1921. Serial No. 434,785.

To all whom it may concern:

Be it known that we, FRED C. HOFFER and J FRANK SMEDLEY, both citizens of the United States, residing at Los Angeles and Pasadena, respectively, in the county of Los Angeles and State of California, have invented a new and useful Street-Sweeper, of which the following is a specification.

This invention relates to improvements in street sweepers of the type embodied in our Patents #1,256,561, granted Feb. 16, 1918, and #1,254,803, granted Jan. 29, 1918.

The primary object of the invention is to provide for a comparatively small and efficient vehicle street sweeper which is constructed so that a commercial vehicle, preferably a motorcycle, may be employed as the propelling, operating and supporting medium for the street sweeping means.

Another object of this invention is to provide a frame construction for a street sweeper which will permit of the attachment of a vehicle frame thereto and the use of the motive power of the vehicle for the operation of the street sweeping means in a reliable and effective manner.

Another object of the invention is to provide a means for eliminating scattering of dust during the sweeping operation which will cause all of the dust and rubbish swept up by a rotary brush forming part of the device to be deposited within receptacles carried by the sweeper.

A further object is to generally improve and simplify the construction and operation of street sweepers of the type hereinbefore described so as to render them inexpensive to manufacture, relatively light in weight and thoroughly efficient in operation.

The accompanying drawings illustrate the invention:

Figure 1 is a side elevation of the sweeper constructed in accordance with the invention.

Fig. 2 is a side elevation of the sweeper shown for the most part in section with the vehicle frame illustrated in dotted lines and the sweeping means shown in out-of-the-way position.

Fig. 3 is a top plan view of the entire sweeper.

Fig. 4 is a top plan view of the sweeper being broken away in part and shown removed from the vehicle frame.

Fig. 5 is a front elevation of the sweeper with one of the doors broken away to show the rubbish and dust receptacle; and

Fig. 6 is an enlarged fragmentary detail perspective view of the brush supporting frame and brush operating elements.

Referring to the drawings, 1 designates a vehicle frame which, in this instance, is a motorcycle frame, and supports a motor 2, luggage carrier 3, steering means or handle bars 4, seat 5 and rear wheel 6. It will be noted that the vehicle frame is not changed in construction, but the front wheel for the frame is removed to permit of the attachment to the street sweeper, as will be later more fully described.

A main frame 7 comprising bars 8 is connected with the vehicle frame 1, the bars 8 being located upon opposite sides of the vehicle frame and connected at their rear ends by strap members 9 with the rear end 75 of the frame 1. These bars 8 extend upwardly and outwardly away from the frame 1 to points considerably in advance of the frame and at their forward ends are secured at 10 to the sides of a substantially rectangular frame 11 adapted for supporting rubbish receiving means. The frame 11 comprises upper and lower horizontal bars 12 and 13 which are joined at their ends by vertical bars 14. Wheels 15 and 16 are connected by 85 steering knuckles 17 and brackets 18 with the bars 14 and support the frame 11. The bar 13 is considerably shorter than the one 12 so that it may lie between the wheels 15 and 16 and the bar 12 extends beyond the 90 wheels, the bars 14 being outwardly offset as at 19, said outwardly opposite portions overhanging the wheels.

A vertical steering post 20 is mounted upon the frame 11 and connected by a suitable means 21 with the wheels or steering knuckles 17 of the wheels 15 and 16. The post 20 has an operating bar 21 secured to its upper end intermediate the ends thereof and links 22 connect the bar 21 with a similar bar 23 carried by the steering means 4 of the vehicle frame 1.

The frame 7 is suitably reinforced, there being provided intermediate the ends thereof a brace bar 24 secured to the bars 8 by angle members 25. The frame 1 is connected with the bar 24 as at 25'. Extending rearwardly from and connected with the

bar 24 at points on opposite sides of the center thereof are brace rods 26 which are connected at their rear ends as at 27 with the bars 8 at points near the rear ends of said bars 8. It is between these rods 26 that the vehicle frame is located.

Connected with and depending from the main frame 7 is a brush supporting frame 28 which comprises adjustable sectional brush supporting arms 29 which are mounted for swinging movement at their upper ends upon a horizontal shaft 30. The shaft 30 is mounted in bearings 31 secured to and depending from the bars 8. A brace rod 32 is mounted between and connected with the arms 29 to give suitable rigidity to the frame 28. A rotary cylindrical brush 33 is mounted between the arms 29 and connected with the lower ends thereof, there being provided trunnions 34, at the ends of the brush, which extend through the lower ends of the arms 29.

There is provided means for raising and lowering the brush which comprises a lever 35 pivoted at its lower end at 36 to one of the bars 8 of the main frame 7 at a point upon one side of the vehicle frame. A notched quadrant 37 is secured to said bar 8, and lever locking means 38 is carried by the lever and co-operates with the quadrant 37. A horizontal shaft 39 is mounted in suitable bearings 40 carried by the bars 8 of the frame 7 and extends across said frame parallel or adjacent to the brace bar 24. A rocker arm 41 is connected with the shaft 39 and extends downwardly therefrom. A rod or link 42 is pivotally connected as at 43 with the rocker arm 41 and is pivoted as at 44 to the lever 35 intermediate the ends of said lever so that upon the shifting of the lever a rotary motion will be given the shaft 39. Extending rearwardly and downwardly from the ends of and secured to the shaft 39 are arms 45, the rear ends of which are pivotally connected as at 46 to the upper ends of rods 47. The rods 47 are secured as at 48 to the brush supporting arms 29 near the lower ends of said arms whereby upon the upward movement of the arms 45 an upward pull will be communicated to the arms 29 through the rods 47 and the brush supporting frame and brush will be lifted into out-of-the-way position.

There is provided a driving means for operating the brush 33 and other parts of the device which will be later more fully described, which comprises a clutch sprocket 49 connected with suitable clutch means 50 operatively associated in the customary manner with the motor 2 of the vehicle. Suitable means 51 is provided for operating the clutch and a catch member 52 serves to hold the means 51 in operative position. Mounted in a bearing 53 which is carried

upon the rear face of the bar 24 is a sprocket 54 and a chain 55 is mounted upon the sprockets 49 and 54. Mounted in a bearing 56 extending rearwardly from the bar 24 and in a bearing 57 carried upon one of the rods 26 is a horizontal shaft 58 carrying a sprocket 59 which meshes with the lower half of the chain 55, as shown clearly in Fig. 2 of the drawings. This arrangement provides for a reversal of the direction of rotation of the shaft 58 as compared to the direction of rotation of the sprockets 49 and 54. The shaft 30 has a sprocket 60 fixed thereto and a chain 61 is mounted upon said sprocket and upon a sprocket 62 which is fixed to the shaft 58. Fixed to the ends of the shaft 30 are sprockets 63 having chains 64 mounted thereon. These chains are mounted upon relatively large sprockets 65 that are fixed to the outer ends of the trunnions 34 of the brush 33. It will be noted that the sprockets 49 and 54 are rotated counter-clockwise and that it is necessary to rotate the brush 33 in a clockwise direction in order to provide for an effective sweeping action. By having the sprocket 59 engaged with the under side of the chain 55, the shaft 58, sprocket 62, sprockets 60, 63, 65 of the brush 33 are rotated clockwise.

A cooling fan 66 is rotatably mounted upon a bracket 67 fixed to the bar 24 and is operated by pulleys 68 and 69 fixed to the fan and shaft 30 respectively, there being provided a belt 70 for operatively connecting said pulleys. The fan 66 is positioned so that it will force air upon and cool the motor of the vehicle.

A semicylindrical dust hood 71 is mounted over the brush 33 in close relation thereto and fixed to the arms 29 to prevent the brush from scattering dust. In addition to this means for preventing the scattering of dust there is provided a cover 72 which consists of side portions 73 secured to and depending from the bars 8 of the frame 7, the forward ends of the side portions being cut away and curved as at 73' so as to lie close to the wheels 15 and 16. The upper forward ends of the side portions of the covering are secured to the frame 11 and said side portions extend rearwardly to a point back of the brush 33 at which points an angular back portion 74 is connected therewith, said back portion being secured to the bars 8. A top or cover plate 75 is mounted upon the upper sides of the bars 8 and covers the space therebetween from the bar to the frame 11, the plate being secured to both the bar and frame. The cover 72 and plate 75 provide a complete covering for the brush and other co-operating elements of the sweeper and prevent the scattering of dust. The lower edges of the side and back portions 73 and 74 of the cover 72 may, if desired, be provided with flexible strips 76.

which are adapted to engage the ground or surface to be swept and provide a comparatively dust-tight covering.

Mounted upon the bar 13 of the frame 11 5 and extending forwardly rearwardly from said bar is a plate 77 for supporting the rubbish receiving means which preferably consists of two flexible bags or similar receptacles 78. An angle supporting bar 79 10 is held in supporting position by strap members 80 which are secured to the bars 8 and extend downwardly and inwardly therefrom to points where connected with the bar 79. Supporting or bracing elements 81 are secured to the plate 77, extend rearwardly 15 over the bar 79 and are connected with the bar 24 as at 82. Mounted upon a suitable base 83 supported on the plate 77 and bar 79 is a rotary exhaust pump 84 having an intake elbow 85 extending outwardly 20 from one side thereof and braced by a take-up rod 86 which is connected with the casing for the pump and bar 24.

An elongated suction member 87 is connected with the elbow and is open along its lower long side for the entire length thereof, such length being substantially equal to that of the brush 33. This member 87 is supported by hangers 88, 89 connected with the bars 8 and straps 80. The lower open side of the member 87 is located in front and adjacent to the lower side of the brush 33 so that the rubbish and dust swept up by the brush will be deposited or drawn into the member 87. A loose flexible strip 89' is secured along the upper edge of the open end of the member 87 and to the adjacent end of the hood 71 to prevent the rubbish from being thrown upwardly from the brush.

To provide for the catching of the rubbish and to insure of its being sucked through the member 87, as will be later more fully described, a means carried upon the lower end of the member 87 and adapted to receive the rubbish swept up by the brush is used. This means comprises a rectangular strip or plate 90 which is hinged as at 91 to the lower edge of the open side 0 of the member 87, the width of this plate being such as will provide for the approximate closing of the opening in the lower end of said member 87. A horizontal shaft 92 is rotatably mounted in bearings 93 5 that are carried on the supporting elements 81 and downwardly and rearwardly extending arms 94 are fixed to the ends of the shaft 92. Links 95 are connected with the lower ends of the arms 94 and with the ends 10 of the plate 90 so as to support the plate in operative position and provide for the movement thereof into closing position. A rocker arm 96 is fixed to the shaft 92 and has connected therewith an operating rod 97 which extends rearwardly and upwardly

to and is connected with the lever 35 intermediate the ends of said lever. By pulling the lever rearwardly, the brush will be lifted as described and it will be seen that the shaft 92 will be rotated so as to cause the arms 70 94 and links 95 to be pulled upwardly and effect the closing movement of the plate 90.

The means for operating the pump 84 comprises a sprocket 101 mounted upon the shaft 102 of the pump. A chain 103 is 75 mounted upon the sprocket 102 and upon a sprocket 104 fixed to the shaft 30. Upon rotation of the shaft 30 which causes the operation of the brush 33, the pump 84 will operate to create a suction in the member 87. 80 An outlet pipe 105 for the pump 84 is connected with a dust separating and rubbish distributing chamber 106 which has two outlets 106' communicating with the receptacles 78 and two dust outlets 107 which have 85 porous dust bags 108 connected therewith. The receptacles 78 are removably secured to cover members 109 by straps 109', the cover members being supported from the chamber 106 and provided with openings 110 whereby 90 inspection of the receptacles may be made without removing them. The receptacles lie in flanged pans 111 and are mounted upon the plate 77 and these openings 110 are closed by caps 110'. A supply of these receptacles 78 may be carried upon the luggage carrier 3, as shown in the drawings.

The front of the sweeper is closed by doors 112 and 113 having a common hinge 114 and held in position by latches 115. These 100 doors are bulged outwardly as at 116 so as to accommodate the receptacles 78.

The clutch means 50 and brush 33 are normally in inoperative positions, the brush being held spaced from the ground, as shown 105 in Fig. 2 of the drawings. To lower the brush into sweeping position, the lever 35 is released and pushed forwardly pushing the rod 42 which is connected with the rocker arm 41 and causing the shaft 39 to be rotated clockwise. This rotation of the shaft moves the arms 45 downwardly and as said arms are connected with the brush through rods 47, the brush will be lowered. The clutch operating member 51 is then pushed 110 downwardly until it is automatically engaged and held in operative position by the catch 52. The sprocket 49 then rotates counter-clockwise and through the chain 55 rotates the sprocket 54 in a corresponding direction. The sprocket 59 meshing with the lower side of the chain 55 is rotated clockwise causing a corresponding movement to be given the shaft 58, sprocket 62, chain 61, sprocket 60, shaft 30, sprocket 63, chain 64, 115 sprocket 65 and brush 33. The tension of the chain 64 may be regulated by the adjustment of the sectional arms 29 which support the brush. At the time that the clutch means 50 is allowed to operate, the pump 84 120 130

is operated through the sprocket 104, chain 103 and sprocket 101. As the brush rotates, the rubbish and dust swept up thereby will be thrown upon the plate 90 at the lower 5 end of the suction member 87 and into said suction member wherein the suction will cause the rubbish and dust to be drawn into the pump 84 and forced into the member 106. The rubbish received in the member 106 will be directed into the receptacles 105, whereas the dust will be blown through the discharge openings 107 into the porous 10 dust bags 108. The air blown into the receptacles 78 will escape through the screened 15 outlet openings 110, and will not be dust-laden upon escapement owing to the screens. This is also true of the escapement of the air from the bags 108. In order to suck the 20 rubbish and dust collected in the lower end of the receptacles 87 and from the plate 90 into the pump 84 the operator grasps the lever 35 and moves it rearwardly causing a pull on the rod 92 and the rocker arm 96 to rotate the shaft 95. This pulls upwardly 25 on the arms 94 and links 95, causing the plate 90 to be moved into closing or semi-closing position, as shown in Fig. 2 of the drawings, and the brush to be raised. This creates a greater suction at the lower end of 30 the member 87 and all particles of rubbish and dust will be sucked into the pump 84 and blown into the receptacles therefor.

Should the brush 33 encounter an obstruction during the sweeping operation, it will 35 move upwardly owing to the rearwardly and downwardly inclined arms 29 mounted upon the shaft 30. The inclination of the arms 29 provides for the upward or downward movement of the brush to permit it to 40 engage in sinks or depressions or to ride over bumps in the road or pavement, thus providing for a thorough sweeping action on rough as well as smooth streets. As the brush wears down the arms 29 may be "let 45 out" so as to insure a reliable contact of the brush with the street and to cause the brush to remain at same relation to the member 87. The relation of the brush to the member 87 is essential since the rubbish swept up 50 by the brush must be directed into the open end of the member 87 to insure a proper operation of the machine.

We claim:

1. In a street sweeper, a brush supporting 55 frame, a rotary brush mounted upon the frame, means to rotate the brush, a dust hood mounted over and covering the upper

portion of the brush, a suction member located adjacent the brush and adapted to receive rubbish swept up thereby, means to 60 create a suction in said suction member, a plate hinged to the open end of said suction member, means to move the plate toward and away from said open end to effect the closing and opening thereof, and a flexible 65 strip secured to the suction member and hood to prevent rubbish swept up by the brush from being thrown upwardly away from the suction member.

2. In a street sweeper, a brush supporting 70 frame, a rotary sweeping brush mounted on the frame, means to rotate said brush, a suction member having one end located adjacent to and in advance of the brush, means to create a suction in said suction member, a 75 dust hood mounted over and covering the upper portion of the brush, and a flexible strip secured to the suction member and hood.

3. A street sweeper comprising a brush 80 supporting frame, a rotary brush carried by the frame, a suction member having one end open and located to receive rubbish swept up by the brush, means to open and close the open end of said suction member, rubbish receptacles, means to create a suction in said member and deposit rubbish into the receptacles, means to raise and lower the brush supporting frame, a hood carried by said brush supporting frame and extending 90 over the upper side of the brush, and a flexible strip secured to the suction member and hood to prevent rubbish swept up by the brush from being thrown above the open 95 end of the suction member.

4. In a street sweeper, a brush supporting frame, means to rotate the brush, a suction member having one end open and located to receive rubbish swept up by the brush, a plate hinged to the lower edge of the open 100 end of said member and adapted to be moved up or down to effect the opening or closing of said open end, means for controlling the movement of the plate, and means to create a suction in said suction 105 member.

In testimony whereof, we have hereunto set our hands at Los Angeles, California, this 16th day of January, 1917.
